UNITED STATES PATENT OFFICE

163,985

CIRCUIT INTERRUPTER

Benjamin P. Baker, Turtle Creek, and Winthrop M. Leeds, Forest Hills, Pa., assignors to Westinghouse Electric Corporation, a corporation of Pennsylvania

Application July 15, 1950, Serial No. 11,211

Term of patent 14 years

(Cl. D26—11)

To all whom it may concern:

Be it known that we, Benjamin P. Baker and Winthrop M. Leeds, citizens of the United States, residing respectively at Turtle Creek and Forest Hills, in the county of Allegheny and State of Pennsylvania, have invented a new, original, and ornamental Design for a Circuit Interrupter, of which the following is a specification, reference being had to the accompanying drawings, forming a part hereof.

Fig. 1 is a side elevational view of a circuit interrupter showing our new design;

Fig. 2 is an end elevational view; and,

Fig. 3 is a plan view in section taken along the line 111—111 of Fig. 1 looking in the direction of the arrows.

The dominant features of our design reside in the portions illustrated in the drawings in solid lines.

We claim:

The ornamental design for a circuit interrupter, substantially as shown and described.

BENJAMIN P. BAKER.
WINTHROP M. LEEDS.
